UNITED STATES PATENT OFFICE

HENRY L. PITMAN, OF WESTFIELD, NEW JERSEY, ASSIGNOR, BY MESNE ASSIGNMENTS, TO ELLIOTT-FISHER COMPANY, OF NEW YORK, N. Y., A CORPORATION OF DELAWARE

TYPEWRITING MACHINE

Application filed February 11, 1926. Serial No. 87,533.

This invention relates to tabulating and carriage-return mechanisms for typewriting machines of the Underwood type, where power-driven means operate to line-space the platen and return the platen-carriage to a new line-starting position and from which position tabulating keys and associated means quickly reposition the carriage denominationaly within determined column-fields.

One object of this invention is to provide means whereby an operative may interrupt the power-driven return movement of the carriage by operating a tabulating key and cause the immediate positioning of the carriage for writing in an intermediate place on the work-sheet without fully returning the carriage to the initial line-starting position. This is of great advantage in cases where entries are written in different columns on the work-sheet. Thus, as soon as the power-driven means has returned the carriage, so that the column on the work-sheet in which it is desired to make an entry is past the printing point, a tabulating key may be depressed, and the return movement of the carriage is thereby stopped for lack of driving power, and a tabulating movement of the carriage toward the left immediately occurs, under the power of its own driving spring, and is arrested when a column-stop on the carriage strikes the decimal-stop raised in its path by the tabulating key.

By means of suitable connections the movement of the usual universal bar coacting with the decimal tabulating stops to disengage the carriage-feed rack from its pinion is also used to simultaneously disengage the carriage-return driving mechanism. This is preferably accomplished by extending the shaft on which the tabulating universal bar is mounted and fastening an arm thereon to reach and engage the usual linkage by means of which the carriage-return mechanism is engaged, but which, according to the present invention, may be also used to disengage the carriage-return mechanism.

Another object of this invention is to provide means whereby starting and stopping of the motor may be controlled by means of the same circuit-closing device or switch regular-

ly provided for the carriage-return mechanism. This device is actuated upon releasing a train of spring-pressed linkage, by means of which the carriage-return mechanism is engaged. A bar pivoted to this linkage extends toward and interlocks with the circuit-closing device, so as to normally keep it open. When the linkage is released to engage the carriage-return mechanism this bar is withdrawn, and the circuit-closing device which includes a spring-pressed arm is closed.

In the present invention, the switch-bar is connected to the carriage-return linkage in such a way that it may be operated independently of said linkage, making it possible to disengage the carriage-return mechanism without stopping the motor when a tabulating key is operated, or to operate the circuit-closing device independently of the carriage-return mechanism linkage, or to operate the circuit-closing device in the usual way when the carriage-return mechanism is engaged or disengaged. The actuating element for the circuit-closing device or switch is preferably connected to the carriage-return mechanism linkage by means of a pin and inclined slot device, which disengages the carriage-return mechanism when a tabulating key is operated.

The carriage-return mechanism is engaged by pressing the usual carriage-return key, or the engagement is effected automatically by the usual means associated with the left-hand marginal carriage stop.

Other features and advantages will hereinafter appear.

In the accompanying drawings, Figure 1 is a sectional elevation of an Underwood-Hanson combined typewriting and computing machine, and shows only such part of the typewriter mechanism and computing mechanism as is necessary to illustrate the invention.

Figure 2 is a detail view of the principal letter-feeding elements.

Figure 3 is a view of the switch for starting and stopping the motor which operates the carriage-return mechanism and other devices of this invention.

Figure 4 is a skeleton perspective view of the tabulating mechanism and the means by

which the tappet-supporting member is withdrawn.

Figure 5 is a rear view of some of the parts shown in Figure 4.

Figure 6 is a detail perspective view of the pin-and-slot connection for the switch-actuating element.

Figure 7 is a detail view showing the relation of the parts when a tabulating key is operated and the tappet-supporting member is about to be withdrawn.

Figure 8 is a detail view showing the tappet-supporting member withdrawn, and also showing the means by which it is latched in its withdrawn position.

Figure 9 is a detail view showing the operation of the flexible connection as it yields, if the operating pin is projected against the arm that withdraws the tappet-supporting member.

Figure 10 is a detail view showing the relation of the parts when the carriage-return mechanism alone is engaged.

Figure 11 is a diagram showing the electrical connections.

The Underwood typewriter to which this invention is applied, is provided with a decimal tabulating mechanism, which includes keys 11 upon levers 12 fulcrumed at 13. The rear ends 14 of said levers, when operated, raise decimal-stops 15, so that the upper ends 15^a thereof are in the path of column-stops 16 on the typewriter-carriage 17. The decimal-stops and tabulating keys are retracted against a stop 17^a by springs 18 applied to said decimal-stops. Each decimal-stop 15 has a notch 19 to engage a universal bar 20 mounted upon a shaft 21. Said universal bar, when operated by any of the decimal-stops when a tabulating key is depressed, disengages a carriage-feed rack 22 from its pinion 23 by means which include an arm 24, a link 25 and a lever 26. Said lever is pivoted at 27 and connected to said link at 28 and carries a roll 29, which lifts the feed rack upward and holds it disengaged from its pinion during the tabulating movement of the carriage.

Numeral-keys 30 and alphabet-keys 31 by means of the usual key-levers, not shown, and bell-cranks 32, partly shown, swinging type-bars 33 upwardly and rearwardly about a fulcrum 34 to print against a platen 35 around which a work-sheet, not shown, may be fed. Heels 36 upon the type-bars actuate a universal bar 37 connected to a dog-rocker 38, which includes a fixed dog 39 and a stepping dog 40. Said dogs co-operate with an escapement-wheel 41 to which is connected the pinion 23. The carriage is propelled in a letter-feeding or tabulating direction by a spring-motor 42.

When the carriage moves in letter-spacing and reaches a line-end marginal carriage-stop, not shown, a lug 43 on the car-

riage actuates a cam-lever, not shown, on said marginal stop to swing a marginal stop-rack 44 about a fulcrum 45. Pivotedly connected to said marginal stop-rack at 46 is a link 47 which extends downwardly and is connected to one end of a lever 48 pivoted upon the typewriter-frame 49 at 50. The other end of the lever 48, when actuated, engages a pin 51 fastened in the side of a carriage-return trip-link 52 and lifts said trip-link, which is pulled rearwardly by a spring 53. Said trip-link is normally held by a plate 54 which engages a notch 52^a in said link 52. The rear end of the link is pivotally connected to an arm 55 fast to a shaft 56. As the carriage in its letter-feeding movement or otherwise reaches the line-end marginal-stop, the carriage-return trip-link 52 is released from its holding plate and its movement by the spring 53 causes the rotation of the shaft 56. The carriage-return trip-link may also be released by means of a manually operated lever 55^a pivoted on the typewriter-frame at 56^a. Said lever when operated raises the forward end of the trip-link 52 to release it from the plate 54 through the camming of a by-pass pawl 57 by the tip 57^a of said lever as it is operated. The lever 55^a is returned to its normal position against a stud 58^a by a spring 59^a and is ineffective to release the link on account of said by-pass pawl. Fastened to said shaft 56 is another arm 58 which is connected by means of a link 59 to an arm 60 fastened to a shaft 61 upon which is fastened an arm 62, which engages a slideable clutch-member 63. As the shaft 61 is rotated by means of the aforesaid connections through the movement of the link 52, the clutch-member 63 actuated thereby slides into engagement with a clutch-member 65 keyed to a shaft 66. Said shaft 66 has its bearing in a bracket 67 attached to the typewriter-frame 49 in the usual manner. A pulley 68 is keyed to said shaft 66, and by means of a belt 122 is connected to a driving motor 70. Said driving motor 70 is controlled by a switch indicated at 71, Figures 3 and 11, actuated by a connection from the link 52 to an arm 72, fastened to the shaft 56 to operate a switch-bar 77. In the end of said arm 72 is a stud 73, which includes a shoulder 74 and a head 75, to be assembled through a cam-slot 76 in the end of the switch-bar 77, see Figure 6. After the cam-slot 76 has been placed over said head 75, the stud 73 may be given a quarter turn, so as to retain the end of the bar 77 between the head 75 and the shoulder 74; the stud 73 then being secured to the arm 72 by any suitable means, as by a lock-nut 73^a. The bar 77 is slidably supported upon an arm 78 and between pins 79 projecting from said arm. The purpose of said arm 78 will presently be described. It will be seen that, as said

shaft 56 is rotated, as when the clutch-members 63 and 65 are engaged, Figure 10, the bar 77 will move longitudinally to close the switch contained within a casing 77. 5 The bar 77 has slidably mounted thereon a member 69 resiliently connected by a spring 69^a, and operative to cushion said member when engaging the switch to close it, so that after closing said switch the bar 77 may 10 have an excess movement during which the spring 69^a yields.

When the typewriter is used with a computing mechanism, there is mounted on its carriage tappets 80 supported by rods 81 and 15 82, the rod 81 serving as a fulcrum for the tappets 80, which are raised by the usual tappet-supporting member 83. Said tappet-supporting member 83 is coextensive with a series of jacks 84 pivoted at 85 and engageable by a one-way pawl 87 mounted upon each tappet 80, and each tappet is upheld as it rides over the tappet-supporting member 83 by means of a roll 87^a fastened to said tappet. In this manner, the carriage, moving step by 20 step through a computing zone, operates at each step one of the jacks 84 and causes a downward thrust of a rod 88, to select in the usual manner one of the computing machine pin-bars which are not shown. The computing mechanism is of the type shown in the patent to O. Minton, No. 1,280,065, dated September 24, 1918. The tappet-supporting member 83 is supported between arms 89 fastened to a rock-shaft 90, which is pivoted 25 between brackets, not shown, upon the typewriter-frame 49. The usual spring-device 91, described in the patent to W. L. Gumprecht, No. 1,268,565, dated June 4, 1918, operates to keep the tappet-supporting member 83 in 30 an effective position to raise each tappet 80, so that it may engage the jacks 84.

When tabulating the carriage it is desirable to withdraw the tappet-supporting member 83, so that the pawl 87 on the tappet will not 35 operate the jacks 84 during the comparatively rapid movement of the carriage as it is tabulated. The withdrawal of the tappet-member 83 is effective against the reaction of the spring-device 91, and to avoid putting the 40 burden of overcoming this reaction upon the tabulating key, means are provided to withdraw the tappet-supporting member 83 by power when a tabulating key is operated. To this end, there is mounted upon the rock-shaft 90 an arm 92, which has a cam-formation 93, see Figure 5. When a tabulating key 45 is operated, there is projected into the plane of this cam-formation 93 a pin 94, said pin being projected through a hole 95 in the web 50 of the pulley 68. This pin may be mounted upon a disk 96 which slides upon a bearing 97 formed upon the bracket 67. To slide the pin 94 forward and backward a groove 98 is formed in a hub of said disk 96, to be engaged 55 by a pair of arms 99 mounted on a shaft

100, and yieldably connected thereto by means of a spring 118. One end of said spring is fastened to the shaft 100 by means of a collar 119, and the other end presses the arms 99 which is held by a stud 120 driven through 70 a slot 120^a in a hub 121^a of the arms 99 into the shaft 100. Should the pin 94 be in a position where its projection would be obstructed by the arm 92, the spring 118 will yield until the pin has passed said arm. Said shaft 100 75 is pivotally supported in a hole 101 in the tabulator stop frame and in a hole 102 in a lug 121 fastened to the bracket 67. To rotate said shaft 100 and project the pin 94 into the plane of the cam-formation 93 whenever a 80 tabulating key is operated, said shaft is further provided with an arm 103 fastened thereto and connected by means of a link 104 to the link 25, which is used to disengage the carriage-feedrack. It will be remembered 85 that this link 25, connected to the universal bar 20 by means of the arm 24, is operated whenever a tabulating key is depressed, and is effective to rotate the shaft 100, to drive the pin 94 into the plane of the cam-formation 93 and the motor 70 is simultaneously started to drive the belt 122, to cause the pulley 68 and pin 94 to revolve, to rock the shaft 90.

To start the motor, the depression of any tabulating key vibrates the arm 78 provided 95 with the pin 79, carrying the forward slotted end of the bar 77, and, as the arm 72 and its stud 73 are at this time stationary, the bar 77 is shifted rearwardly, due to the inclination of cam-slot 76, to close the switch 100 71, start the motor, rotate the pulley 68 cause the projected pin 94 as it revolves to displace the arm 92, to rock the shaft 90, and effect the withdrawal of the tappet-supporting member 83. 105

It will be seen that after the revolving pin 94 passes the cam-formation 93, the tappet-supporting member 83 will return to its tappet raising position again, and, to prevent this until the tabulating key is released, a 110 latch 105 is provided, that is pivoted to one of the arms 89 at 106, and is pressed by a spring 107, so that normally an extension 108 of said latch 105 bears against the shaft 100. When a tabulating key is depressed 115 causing the shaft 100 to rotate, an arm 109 thereon raises said latch by means of a lug 110 projecting from said latch. As the tappet supporting member 83 is withdrawn, the latch is pulled rearwardly and the lug 110 falls 120 behind a holding edge 111 on the arm 109.

It will be seen that when the tabulating key is released the arm 109 will be withdrawn from said lug 110, and the tappet-supporting member resumes its normal position. 125

Heretofore, in an automatic carriage return, there was no way of stopping the carriage-return movement until the carriage had reached the right-hand marginal carriage-stop and rotated a shaft 112 by the usual 130

means, which included a dog 113 keyed to said shaft 112 and actuated by the lug 43. As said shaft 112 is rotated it disengages the clutch-elements 63 and 65 by means which 5 include an arm 114, fastened to said shaft 112, a link 115, a sliding member 116 and an arm 117 fastened to the shaft 61. Details of the means associated with the left and right hand marginal carriage-stops to engage 10 and disengage the carriage-return mechanism, are set forth in the patent to R. F. Hoyt, No. 1,238,919, dated September 4, 1917.

Previously, whenever it was desired to 15 make an entry in an intermediate column on the work-sheet or a correction in a computing zone, it was necessary to always return the carriage to its line-starting position as determined by the right-hand marginal carriage-stop, and then to tabulate anew to the 20 place where the entry was to be made. If several columns intervened between the starting point and the place the entry was to be made, such columns could only be skipped by successive operations of the tabulating keys. 25 To avoid this, means are provided so that, as soon as the carriage has returned and the column in which it is desired to make the next entry is past the printing point, the return movement of the carriage may be 30 stopped by pressing the proper denominational tabulating key. The carriage as soon as its return movement is stopped for lack of driving power will be immediately tabulated under the power of its own drum to the 35 denominational column position according to the key depressed, and said key is held depressed until the carriage is thus tabulated. To accomplish this the previously-mentioned 40 arm 78 has a camming edge 123 co-operative with the surface 124 of the stud 73, and effective whenever a tabulating key is depressed to cam the arm 72 aside, thereby causing the restoration of the linkage 58-62 which has effected the engagement of the carriage-return 45 clutch-members 63 and 65. The circuit to the motor, however, is not broken as long as the tabulating key is depressed, so that the tappet-support 83 is withdrawn in the manner described, and the bar 77 held in its circuit-closing position until the tabulating key 50 is released.

It will be noted that the depression of the carriage-return key starts the motor 70 and closes a clutch 63-65, whereby the motor 55 will drive the carriage in a carriage-return direction to a marginal-stop position, which determines the line-starting position for the carriage automatically and independently of the carriage-return key and disables the 60 motor-clutch to arrest the carriage; that the carriage-spring is always effective to drive the carriage in letter-spacing or column-spacing direction when a tabulating key is depressed; that the carriage-return motor 65 overcomes the opposition of the carriage-

spring in returning the carriage; that, when the tabulating key is depressed after a carriage-return movement is initiated, the carriage is disconnected from the rotating return motor and is brought to a stop from lack of motor-driving power, the carriage responding to the tension of its own spring until the carriage-stop strikes the tabulator-stop raised in its path, by the depression of the tabulating key; that the depression of any denominational tabulating key vibrates a universal bar having camming connections that effect the separation of the carriage-feed rack from its feeding and holding pinion to release the carriage to its driving spring, and restores the key-released trip-link 52 to its normal position, but does not withdraw the switch-bar 77 to break the circuit to the return motor, which continues to rotate to prevent the accidental restoration of the tappet-roller 83 until the carriage has fully advanced to the tabulating position within a column-area; that, when the tabulating advance of the carriage is completed and the tabulating key is released, the restoration of the parts from the Figure 8 positions to the positions of Figures 7 and 9 is effected by the return of the universal bar 20 where the lifting of the link 25 rocks the shaft 100 to withdraw the pin 94, vibrates the arm 109 to release the latch 105 to restore the roller 83 to lift the tappet 80, and vibrates a jack 84 corresponding to the decimal value of the key depressed; that the restoration of the universal bar also vibrates the arm 78 to effect the withdrawal of the switch-bar 77 to open the switch 71 and stop the motor 70; that an operator can readily and expertly manipulate the tabulating keys to cut into the carriage-returning movement very close to the right-hand margin of a column-area or even between adjoining column-fields, and then immediately arrest the carriage at a denominational position therein, thus avoiding the useless operation of fully restoring the carriage rightward and then advancing the carriage, column by column, as heretofore practiced, except where complicated column-skipping mechanism is employed which does not tabulate denominational; 110 and that an operator can limit the returning movement of the carriage to a column-width, if desired, and tabulate directly to the denominational position therein, thus providing an important time and labor saving mode of operation and giving the operator a complete carriage-direction control without removing the hands from the keyboard.

Variations may be resorted to within the scope of the invention, and portions of the 120 improvements may be used without others.

Having thus described my invention, I claim:

1. In a typewriting machine, the combination with a spring-driven carriage, a tabu-

lating mechanism including tabulating keys operable to arrest the spring-driven carriage at column-positions, and a carriage-returning mechanism including a motor and a clutch both rendered operable, by the depression of a key, to effect a carriage-return to a line-starting position determined by a margin-stop, of means actuated by the depression of any tabulating key and operatively connected to open the clutch to the rotating motor and effect the arrest of the returning carriage in advance of said margin-stop position and restore the driving control of the carriage to its spring to advance the carriage to a tabular position determined by the tabulating key, said means including a universal bar vibrated by the tabulating keys and having connections operative to open the clutch previously closed by the carriage-return key, said universal bar connections including a cam-face operable to prevent the restoration of the switch-bar, previously set by the carriage-return key to start the motor, until the universal bar is restored by the released tabulating key.

2. In a tabulator-mechanism for a type-writing machine, the combination with a traveling carriage, an electric motor having a normally open circuit and a normally open carriage-clutch, a carriage-return mechanism operative to close the motor-circuit and close the clutch between the carriage and motor, and a tabulator, of means whereby an operation of said tabulator will break the clutch to release the carriage, without breaking the motor-circuit until the tabulator is released.

3. In a typewriting machine, the combination with a spring-driven letter-feeding and carriage-holding mechanism, means including tabulator-keys operatively connected for releasing and tabulating the carriage in a predetermined column, and key-controlled carriage-return mechanism, whereby said carriage is power driven for a full line length return movement and the power-driving means is silenced, of mechanism operable by any tabulator-key, whereby the full power-driven returning movement of said carriage is disabled without disabling the driving power until the action of the carriage-feeding spring has tabulated the carriage and the tabulator-key is released.

HENRY L. PITMAN.
